EXERCISING WEIGHT

Tony Li, 389 Alcatraz Ave., Apt. 15,
Oakland, Calif. 94618

Filed Dec. 4, 1970, Ser. No. 26,287

Term of patent 14 years

Int. Cl. D21—02

U.S. Cl. D34—5

Fig-1

Fig-2

Fig-3

FIG. 1 is a side elevational view of an exercising weight, showing my new design, the appearance being the same from all sides;

FIG. 2 is an end elevational view, looking at the left end in FIG. 1; and

FIG. 3 is an opposite end elevational view, looking at the right end in FIG. 1.

I claim:

The ornamental design for an exercising weight, as shown and described.
